CLAIM

We claim the ornamental design for a non-ambidextrous charging handle, as shown and described.

DESCRIPTION

FIG. 1 is a top perspective view of the new design of a non-ambidextrous charging handle, according to a first embodiment;

FIG. 2 is a bottom perspective view of the new design of the non-ambidextrous charging handle, according to the first embodiment;

FIG. 3 is a top view of the new design of the non-ambidextrous charging handle, according to the first embodiment;

FIG. 4 is a bottom view of the new design of the non-ambidextrous charging handle, according to the first embodiment;

FIG. 5 is a front view of the new design of the non-ambidextrous charging handle, according to the first embodiment;

FIG. 6 is a rear view of the new design of the non-ambidextrous charging handle, according to the first embodiment;

FIG. 7 is a first side view of the new design of the non-ambidextrous charging handle, according to the first embodiment;

FIG. 8 is a second side view of the new design of the non-ambidextrous charging handle, according to the first embodiment;

FIG. 9 is a top perspective view of the new design of a non-ambidextrous charging handle, according to a second embodiment;

FIG. 10 is a bottom perspective view of the new design of the non-ambidextrous charging handle, according to the second embodiment;

FIG. 11 is a top view of the new design of the non-ambidextrous charging handle, according to the second embodiment;

FIG. 12 is a bottom view of the new design of the non-ambidextrous charging handle, according to the second embodiment;

FIG. 13 is a front view of the new design of the non-ambidextrous charging handle, according to the second embodiment;

FIG. 14 is a rear view of the new design of the non-ambidextrous charging handle, according to the second embodiment;

FIG. 15 is a first side view of the new design of the non-ambidextrous charging handle, according to the second embodiment; and,

(Continued)

FIG. 16 is a second side view of the new design of the non-ambidextrous charging handle, according to the second embodiment.
